[57] CLAIM

The ornamental design for toy doll, as shown and described.

DESCRIPTION

FIG. 1 is a front view of a toy doll showing my new design;

FIG. 2 is a side elevation seen from the left side of the toy doll of FIG. 1, the right side being a substantial mirror image thereof;

FIG. 3 is a rear elevation view of the toy doll of FIG. 1;

FIG. 4 is a plan view of the toy doll of FIG. 1; and

FIG. 5 is a bottom view of the toy doll of FIG. 1.

FIG. 1

FIG. 2

FIG. 3

FIG. 4
